S. L. MCKEE.
EGG TESTER.
APPLICATION FILED JULY 16, 1917.

1,260,783.

Patented Mar. 26, 1918.

By *Watson E. Coleman*

Attorney

UNITED STATES PATENT OFFICE.

STEPHEN L. MCKEE, OF SIOUX FALLS, SOUTH DAKOTA.

EGG-TESTER.

1,260,783.

Specification of Letters Patent. Patented Mar. 26, 1918.

Application filed July 16, 1917. Serial No. 180,882.

To all whom it may concern:

Be it known that I, STEPHEN L. MCKEE, a citizen of the United States, residing at Sioux Falls, in the county of Minnehaha and 5 State of South Dakota, have invented certain new and useful Improvements in Egg-Testers, of which the following is a specification, reference being had to the accompanying drawings.

10 This invention relates to certain improvements in egg testers and it is an object of the invention to provide a device of this general character having novel and improved means whereby eggs may be readily candled 15 with the possibility of light reflecting into the eyes of the operator or candler eliminated.

It is also an object of the invention to provide a device of this general character including a light chamber provided with an egg receiving opening, together with an eye piece supported exteriorly of the light chamber and disposed in a direction toward the egg receiving opening.

20 The invention consists in the details of construction and in the combination and arrangement of the several parts of my improved egg tester wherein certain important advantages are attained and the device rendered simpler, less expensive and otherwise more convenient and advantageous for use, as will be hereinafter more fully set forth.

The novel features of my invention will hereinafter be definitely claimed.

35 In order that my invention may be the better understood I will now proceed to describe the same with reference to the accompanying drawings wherein:

Figure 1 is a view in front elevation of an 40 egg tester constructed in accordance with an embodiment of my invention, with the curtain omitted;

Fig. 2 is a sectional view taken substantially on the line 2—2 of Fig. 1;

45 Fig. 3 is a sectional view taken substantially on the line 3—3 of Fig. 2; and

Fig. 4 is a view in perspective of the curtain employed in connection with my improved device.

50 As disclosed in the accompanying drawings 1 denotes a cylindrical hollow body having the upper end provided with a closure member 2 while the opposite or lower end thereof is open.

55 At substantially its longitudinal center

the body 1 is provided in a wall thereof with a pair of transversely alined egg receiving openings 3, and the marginal portions of each of said openings is slightly rolled inwardly as indicated at 4, so that an egg to be tested may be snugly received therein. As is particularly illustrated in Figs. 1 and 3 it is to be noted that the openings 3 are spaced apart a distance materially less than the diameter of the body 1. At 60 diametrically opposed points inwardly of the openings 3 the body 1 has secured thereto the laterally directed plates 5 extending the entire length of the body 1 and having their outer margins provided with the forwardly 65 directed flanges 6 at right angles thereto. The forward edges of the flanges 6 are inclined downwardly and inwardly to the lower end of the plates 5. The spaces between the upper margins of the flanges 6 70 are closed by the plate 7 whereby said plates 5 and 7 together with the flanges 6 afford a hood. Carried by the plate 7 and in communication with the hood is an eye piece 8 disposed on a predetermined incline to afford 75 visual access within the hood so that an effective test may be had of the eggs seated within the openings 3.

The closure member 2 is provided at substantially its axial center with an opening 9 80 to afford a means whereby an illuminating member such as an electric bulb or the like may be positioned within the body 1 above the openings 3. In practice it has been fully demonstrated that by having a light 85 arranged at the top of the body 1 rays sufficiently penetrate the portions of the eggs within the body 1 to permit an effective testing or candling thereof with the further advantage that in the event an egg does not 90 snugly fit within the opening 3 the rays reflecting therethrough will not be directed toward the eyes of the operator when applied to the outer end of the eye piece 8, as is also true during the removal or placement 95 of an egg. It is also of particular advantage to have the bottom or lower face of the body 1 open so that the heat generated by the illuminating member within the body 1 may escape from within the body.

100 The body 1 is also provided with a downwardly facing clip 10 positioned exteriorly thereof to afford means whereby the body 1 may be readily and conveniently applied 105 into a convenient position for the work. It 110

has also been found of advantage to connect the body 1 and the lower margins of the plates 5 and the flanges 6 with the horizontally disposed strips 11 in order to impart a maximum of strength to the device.

Secured to the outer marginal portion of the plate 7 is the upper edge portion 12 of the curtain C. The curtain C is provided with the inwardly directed end flaps 14 suitably secured to the outer or inclined marginal portions of the flanges 6. The curtain C and the flaps 14 thereof co-act with the plate 7 and the flanges 6 to afford a dark room to facilitate the candling of the eggs arranged within the openings 3.

From the foregoing description, it is thought to be obvious that an egg tester constructed in accordance with my invention is particularly well adapted for use by reason of the convenience and facility with which it may be assembled and operated and it will also be obvious that my invention is susceptible of some change and modification without materially departing from the principle and spirit thereof and for this reason I do not wish to be understood as limiting myself to the precise arrangement and formation of the several parts herein shown in carrying out my invention in practice except as hereinafter claimed.

I claim:

An egg tester comprising a tubular body having its lower end open, the opposite end of the body being provided with means to apply an illuminating member, an egg receiving opening formed in a wall of the body at substantially the longitudinal center thereof, a hood carried by the body and extending in advance of the portion thereof provided with the egg receiving opening, an upstanding eye piece carried by the hood and in communication therewith, said hood comprising oppositely directed lateral plates terminating in forwardly directed flanges, the forward edges of the flanges being inclined downwardly and inwardly to the lower ends of the plates, a top plate bridging the space between the flanges and the plates, and a curtain depending from the forward marginal portion of the top plate and provided with inwardly directed end flaps secured to the inclined marginal portions of the flanges.

In testimony whereof I hereunto affix my signature in the presence of two witnesses.

STEPHEN L. MCKEE.

Witnesses:

J. M. HAGGARDS,
C. H. CRAIG.
